FILTER SHEATH

**Kenneth A. Van Dyck, Rochester, N. Y., assignor
to Eastman Kodak Company, Rochester, N. Y.,
a corporation of New Jersey**

Application March 26, 1953, Serial No. 24,201

Term of patent 3½ years

(Cl. D61—1)

To all whom it may concern:

Be it known that I, Kenneth A. Van Dyck, a citizen of the United States of America, residing in Rochester, in the county of Monroe and State of New York, have invented a new, original, and ornamental Design for Filter Sheath, of which the following is a specification, reference being had to the accompanying drawings, forming a part thereof, in which:

Fig. 1 is a side perspective view of a filter sheath showing my new design;

Fig. 2 is a side elevational view thereof;

Fig. 3 is a sectional view taken on the line 3—3 of Fig. 2.

I claim:

The ornamental design for a filter sheath, as shown.

KENNETH A. VAN DYCK.
